UNITED STATES PATENT OFFICE.

ABNER R. NEFF, OF LONG BEACH, CALIFORNIA.

ELECTRIC POPCORN-POPPER.

1,380,579.

Specification of Letters Patent. Patented June 7, 1921.

Application filed May 31, 1919. Serial No. 300,831.

To all whom it may concern:

Be it known that I, ABNER R. NEFF, a citizen of the United States, residing at Long Beach, in the county of Los Angeles, State 5 of California, have invented new and useful Improvements in Electric Popcorn-Poppers, of which the following is a specification.

This invention relates to electrically heated utensils; and an object of the invention 10 is the provision of an electrically heated pop-corn popper; and the provision, in such a pop-corn popper, of a simple and efficient construction which may be easily and effectively used for the popping of pop-corn.

15 I am not aware that any electrically heated pop-corn popper has been heretofore produced. Whereas a great variety of utensils are now heated by electricity, pop-corn poppers are universally of the old style which 20 are used over a stove or over a slow fire. There are a great many objectionable features to such pop-corn poppers; they necessitate the popping of corn either over a grease producing gas or oil stove or over a 25 hot bed of coals. Neither of these operations is pleasant during the warmer months of the year; and, in general, a great deal of the pleasure of popping corn is taken away by the shortcomings of the old style pop-corn 30 popper. It is an object of my invention to obviate these difficulties and to produce a device which has in it none of these difficulties inherent in the old style pop-corn popper. It is an object of my invention to 35 provide a pop-corn popper which is clean and attractive; and in which only that amount of heat is generated which is necessary to the actual popping of the corn. It is also an object of my invention to provide 40 a construction simple and efficient in itself and, preferably, capable of being used in a variety of manners. Such objects, and further objects and corresponding features of the invention will be best understood from 45 the following detailed description of different forms of pop-corn poppers embodying my invention, reference for this purpose being had to the accompanying drawings in which—

50 Figure 1 is a sectional plan view of the popper taken on line 1—1 of Fig. 2; Fig. 2 is a side elevation of the popper; Fig. 3 is a sectional view taken as indicated by line 3—3 on Fig. 1; Figs. 4 and 5 are enlarged 55 detail sections of modified forms of the pop-

per; Fig. 6 is a sectional view of a popper embodying the invention; Fig. 7 is a plan of the form shown in Fig. 6, the upper cover being removed; and Fig. 8 is an enlarged detailed section taken as indicated by line 8—8 60 on Fig. 7.

In the drawings numeral 10 designates the base or pan of the popper on which is mounted the box shaped cage 11. Attached to base pan 10 there is a handle 12. The handle is 65 preferably made of metal soldered or brazed to the base, but however, any suitable material may be used for the handle such as a composition, wood or some similar material.

The base pan 10 is substantially a shallow 70 tray and is preferably formed from one piece of sheet metal and comprises a bottom 13 and sides 14. The sides 14 are not at right angles with the base 10 but flare slightly outward as shown in the drawings. 75

In the base 10 there is a heating grid 16. The grid 16 is made of a metal or alloy that has sufficient resistance to become heated when an electric current is passed through it. The grid may be any suitable shape and the metal out of which it is made may be either in the form of a wire, a ribbon or a sheet or plate. In Fig. 1 is shown a grid that has been stamped out of a sheet of metal. As shown in the drawings the grid 85 is connected to lead wires 19 which enter the popper through the handle 12 and pass through the handle to the base 10. The wires pass into the base 10 through a hole 35 in the side 14 and connect to the grid as 90 shown in Fig. 1. The grid 16 is preferably made small enough to fit within the base 10 so as to be far enough away from sides 14 to prevent them from becoming heated.

Between the grid 16 and the bottom 13 of 95 base 10 there is a layer of heat insulating material 15. In the preferred form of the invention asbestos is used for this insulation as it not only insulates the grid so that it will not conduct electricity to the bottom 13 but also prevents the bottom from becoming heated when the popper is in operation. With the bottom thus insulated from the grid the popper can be set upon a table or the like without danger to it. Directly on 100 top of the grid there is a thin layer of insulating material 17 which insulates the grid from the cover plate 18 on which the corn is placed. The insulation 17 may be a thin sheet of mica. The protective cover 18 fits 105 110

into the base 10 so as to entirely cover and protect the insulation and heating grid. The cover 18 may be made of sheet metal or of wire netting as shown in Fig. 4. The grid, 5 the insulating layers and the cover 18 may form a unit which may be inserted in or removed from the pan, as a whole.

As shown in the drawings, the sides 14 are high enough to extend above the cover 18. 10 In the corners formed by the cover plate 18 and the sides 14 there are curved sheet metal corner pieces 25. The corner pieces may be attached to the sides by means of screws 26. When the corner pieces 25 are in place they 15 hold the insulations and the grid tightly together and press them against the bottom 13 thereby preventing them from becoming shifted or out of place. The corner pieces also act as a fillet to keep the corn away 20 from the sides of the popper and direct it toward the center where it will be over the heating grid.

The cage 11 comprises sides 20, ends 21 and 22 and a top 28. The cage is a perforated structure and is preferably made of wire netting, as shown in the drawings. The cage 11 is substantially the same in construction and it is the same in purpose as the cage structure used in ordinary corn 30 poppers. The perforated construction allows the operator to see the corn pop and enables him to know when it is done and also prevents the corn from being scattered when it is popped. The sides 20 and the 35 ends 21 and 22 are made of wire netting mounted on a wire frame 23. The bottom part of the frame 23 is made to fit into the base 10 so that it rests on cover 18 and the corner pieces 25 fit over the frame 23 and 40 so as to cover it and hold it tightly against the cover 18. The sides and ends of the cage are firmly clamped between the sides 14 and the corner pieces 25.

In Fig. 5 is shown a form of construction 45 in which no corner pieces are used. In this construction there are indentations or grooves in the sides 14 into which the lower part of frame 23 fits.

The cover 28 comprises a wire frame 32 50 on which is mounted a wire netting or screen 33. The cover is hinged at 27 to end 21. Attached at 29 to end 22 there is a hook 30 which hooks over frame 32 of cover 28 and keeps it closed. The hook 30 is provided 55 with a handle 31 which makes it easy to operate.

The forms of the invention hereinabove 60 described are merely typical and the invention is not limited to such forms as it may be embodied in various forms of popper. For instance, it may take the form shown in Figs. 6, 7 and 8.

In Figs. 6, 7 and 8 is shown a form of construction in which the heating grid, the 65 insulations and the cover are a separate

unit and the cage is constructed so that it can be easily removed from the base pan.

As shown in Fig. 6, the asbestos 15^a, the grid 16^a, and the mica 17^a are held together by the cover 18^a. The cover 18^a extends 7 around the edges of the asbestos and mica and is attached to a rectangular wire frame 40 which is a little smaller than the asbestos 15^a. The heating grid, the insulations and the cover being thus held together form a 7 unit that can be easily set in or removed from the base.

The asbestos 15^a is held away from bottom 13^a by the frame 40 thus leaving a space 41 between them. In the bottom 13^a there are 8 perforations or holes 42 which allow air to circulate between the bottom and the asbestos. This construction prevents the bottom from becoming heated even if the asbestos becomes heated. In this form of the 81 invention the handle 12^a may be attached to the bottom 13^a instead of a side 14^a. The heating unit comprising the grid, the insulations and the cover is held in the base by a frame 44 formed of corner pieces or fillets 91 25^a. The frame 44 fits in the base pan 10^a and is held by fitting under the corrugations 45 near the top of the sides 14^a.

The cage 11^a is made of fine wire netting mounted on a wire frame 46. The frame 91 46 is made to fit in the outside of corrugations 45. In order to place corn in or remove it from the popper the cage is completely disengaged from the base pan. This makes it possible to use the base for other 10 purposes without the cage. The sides 14^a are not continuous at their corner intersections, but are slit there, as indicated at 14^b. This construction allows the sides to have enough spring to allow the frame 44 and the cage 11^a to be attached to and removed from the base with ease.

The entire device may be finished in any desired manner, for instance, it may be nickel or silver plated or it may be enameled. 11

When corn is placed in the popper it comes directly in contact with the cover 18. When current is passed through the grid the heat from said grid passes through the thin mica sheet and heats the cover 18. The corn 11 being in contact with the cover 28 becomes heated and pops in the usual manner. As stated above, the corn is prevented from flying out of the popper by the cage structure. In order to prevent the corn from 120 burning, the operator may conveniently hold the device by the handle and keep the corn agitated in the usual manner.

From the foregoing description it will be seen that throughout the various forms of 125 my invention there are certain characteristic features. Generally speaking, electrically my heated pop-corn popper embodies a holder for the pop-corn, which holder may be in the form of a pan alone or in the 130

form of an all inclosing cage. In a preferred form, the upper cage proper may be removable from the pan, so that the pan may be used either as a popper or for other purposes. Also, in a preferred construction, the heating unit is removable from the pan. I thus provide one unit consisting of the pan, with its handle, the pan having perforations for the passage of electric feed wires. This pan may also be perforated on the bottom to provide for air circulation. Then I provide another unit comprising the electric heating element with its protective and insulating parts; and a means for holding the heating unit in the pan. This holding means may be provided preferably in the form of a fillet, which, as hereinbefore described, directs the corn away from walls of the pan and back to the effective part of the heating element itself; so that the heating element need not extend close to the walls of the pan and so that the pop-corn is kept at all times over the hot part of the heating element. This arrangement keeps the heat well within the structure, and keeps it from radiating out into the surrounding air. My construction concentrates the heat upon the pop-corn rather than wasting it by radiation to the surrounding air. Then the third unit of a preferred form of my device comprises the upper cage which is removably mounted upon the pan. When this upper cage is used the pop-corn is completely inclosed. The upper cage may be removed, either for the purpose of removing the pop-corn from the popper or it may be removed for the purpose of using the pan for other operations.

The foregoing description will now suffice to set forth my real invention; which is not limited to the specific and particular details which I have here described. I have entered into these particular details for the purpose of making my invention fully intelligible in a practical and operative form; and not for the purpose of limiting my invention to these particular details.

Having described a preferred form of my invention, I claim:

- 50 1. An electrically heated pop-corn popper embodying a pan, a heating element therein, a foraminous cage over the top of the pan; the heating element being spaced at its edges from the walls of the pan, and a sloping fillet member around the walls of the pan with its slope leading to a point over the heating element to direct pop-corn away from the walls and over the heating element.
- 55 2. In an electrically heated utensil, a container, a heating element therein with its edges spaced from the sides of the container, and a fillet member in the container with its slope leading to a point over the heating element to direct matter in the container away from its walls and over the heating element.

3. In an electrically heated utensil, a container, a removable heating element therein with its edges spaced from the sides of the container, and a sloping fillet member in the container with its slope leading to a point 70 over the heating element to direct matter in the container away from its walls and over the heating element; said fillet member extending over the edge of the heating element to hold it in place and being removably 75 held in the container.

4. In an electrically heated utensil, a container, and a heating unit therein embodying a heating element having a heat insulating layer on its underside, said container 80 being adapted to receive material upon said heating unit, the unit being spaced above the bottom of the container, and the container bottom being perforated to allow air circulation below the heating unit. 85

5. In an electrically heated utensil, a pan, a heating unit removably placed in the bottom of the pan and embodying a heating element with a heat insulating layer below it, the heating unit being spaced slightly 90 above the pan bottom and the bottom being perforated; the heating element being spaced at its edges all around from the sides of the pan; and a fillet member around the sides of the pan with its lower edge resting 95 on the heating unit to hold it in place.

6. In an electrically heated utensil, a pan, a heating unit removably placed in the bottom of the pan and embodying a heating element with a heat insulating layer below it, the heating unit being spaced slightly 100 above the pan bottom and the bottom being perforated; the heating element being spaced at its edges all around from the sides of the pan; and a fillet member around the sides of the pan with its lower edge resting 105 on the heating unit to hold it in place; the sides of the pan being resilient and having a shoulder which is sprung over the fillet to hold it in place. 110

7. In an electrically heated utensil, a pan, a heating unit removably placed in the bottom of the pan and embodying a heating element with a heat insulating layer below it, the heating unit being spaced slightly above 115 the pan bottom and the bottom being perforated; the heating element being spaced at its edges all around from the sides of the pan; and a fillet member around the sides of the pan with its lower edge resting on the 120 heating unit to hold it in place; the sides of the pan being resilient and having a shoulder which is sprung over the fillet to hold it in place; and a cage removably mounted over the top of the pan. 125

8. An electric heating unit embodying a heating element, a heat insulating layer on one side of the element, and an insulating layer and a protective metal covering on the other side of the element, the metal cov- 130

ering being bent around the edges of the element and heat insulating layer to bind the whole unit together.

9. An electric heating unit embodying a heating element, a heat insulating layer on one side of the element, an insulating layer and a protective metal covering on the other side of the element, the metal covering being bent around the edges of the element and heat insulating layer to bind the whole unit together; and a wire frame around which the edge of the metal covering is bent to form a bead for spacing the heat insulating layer from a surface on which it rests.
10. 10. A corn popper comprising a pan, a handle on said pan, a heating element in said pan, said element being adapted to become heated when an electric current is passed therethrough, and a foraminous cage over the top of the pan.
11. In an electrically heated utensil, a pan, a heating unit removably placed in the lower part of the pan, a fillet member within and around the pan with its lower edge rest-

ing on the heating unit to hold it in place, 25 and the pan walls releasably engaging the outer edge of the fillet member so that the fillet and heating unit may be removed.

12. In an electrically heated utensil, a pan, a heating unit removably placed in the 30 lower part of the pan, a fillet member within and around the pan with its lower edge resting on the heating unit to hold it in place; the sides of the pan being resilient and having a shoulder which is sprung over 35 the fillet to hold it in place.

13. A corn popper comprising a pan, a handle on said pan, a heating element in said pan, said element being adapted to become heated when an electric current is 40 passed therethrough, and a removable foraminous cage over the top of the pan.

In witness that I claim the foregoing I have hereunto subscribed my name this 21st day of May, 1919.

ABNER R. NEFF.

Witness:

VIRGINIA BERNINGER.
